Assistant Examiner — Kathleen L Jones

(57) **CLAIM**

I claim the ornamental design for a laptop computer, as shown and described.

DESCRIPTION

FIG. 1 is a front, top, right perspective view of the claimed design in a first configuration;

FIG. 2 is a top plan view thereof;

FIG. 3 is a bottom plan view thereof;

FIG. 4 a right side elevation view thereof;

FIG. 5 is a left side elevation view thereof;

FIG. 6 is a rear elevation view thereof; and

FIG. 7 is a front elevation view thereof;

FIG. 8 is a front, top, left perspective view of the claimed design in a second configuration;

FIG. 9 is a top plan view thereof;

FIG. 10 is a bottom plan view thereof;

FIG. 11 a right side elevation view thereof;

FIG. 12 is a left side elevation view thereof;

FIG. 13 is a rear elevation view thereof; and,

FIG. 14 is a front elevation view thereof.

The broken lines showing portions of the laptop computer are included for the purpose of illustrating portions of the article and form no part of the claimed design.

1 Claim, 12 Drawing Sheets
